CYLINDER STRUCTURE AND METHOD OF
PRODUCING THE SAME

Frank E. Lonas, New York, and Frederic C. Booth, Mount Vernon, N. Y.; said Booth assignor to said Lonas; Kathryn B. Lonas executrix of said Frank E. Lonas, deceased

Application May 4, 1934, Serial No. 723,906
Renewed August 8, 1936

15 Claims. (Cl. 123—75)

This invention relates to cylinders of internal combustion engines, and particularly to what are known as sleeve valve engines; and the object of the invention is to provide a cylinder which is constructed from a plurality of independently formed parts whereby the separate parts which are composed mainly of tubings, stampings, forgings or the like may be produced at a low manufacturing cost, and which when assembled to form the cylinder structure will produce a light, well-balanced as well as strong and durable structure, and further, whereby the formation of the combustion chamber, intake and exhaust ports as well as circulating chamber is materially simplified; a further object being to provide a cylinder structure of the class described consisting of a main cylinder tube around the head end of which is arranged a supplemental tube between which and the first named tube is formed the water circulating passage or manifold for the cylinder, and wherein a cylinder head structure composed of independently formed parts is arranged and secured within and to both of said tubes, with means in said head structure for forming spark plug receiving chambers; a further object being to provide elongated, flat as well as arc-shaped tubes disposed within and secured to the wall structures of the cylinder tubes for forming intake and exhaust passages through both of said tubes; a further object being to provide means at the lower end of the cylinder structure and the adjacent part of the cylinder housing or casing in which the cylinder structure is mounted for detachably securing said cylinder structure therein; a still further object being to provide an improved method of constructing the cylinders of engines of a plurality of parts as described, and joining said parts together by copper brazing in a hydrogen-electric furnace or in a hydrogen or similar atmosphere to firmly and securely unite the parts at the surface contact areas thereof by copper brazing process to produce in the resulting cylinder structure light, balanced, as well as strong and durable wall structure. One such method is described in the patent to Gillette, No. 1,550,157, Aug. 18, 1925. With these and other objects in view, the invention consists in a cylinder structure and method of producing the same which is more fully hereinafter described and claimed.

The invention is fully disclosed in the following specification, of which the accompanying drawings form a part, in which the separate parts of the improvement are designated by suitable

reference characters in each of the views, and in which:

Fig. 1 is a sectional view through a part of the cylinder structure and housing of an engine made according to our invention.

Fig. 2 is a partial section on the line 2—2 of Fig. 1.

Fig. 3 is a partial section on the line 3—3 of Fig. 2.

Fig. 4 is a bottom plan view of a coupling ring 10 employed for securing the cylinder in place.

Fig. 5 is an expanded or exploded view of the several parts of the cylinder structure made according to our invention, shown partially in section and in broken sectional lines in a continuous 15 view extending from the left of the sheet containing Fig. 5 to the right side of said sheet.

Fig. 6 is a plan view of one of a number of port lining rings or tubes which are employed.

Fig. 7 shows sectional views of two of the tubes 20 shown in Fig. 6 in their relative position to the two receiving recesses of a part of the cylinder shown to the left of said rings on the drawings.

Fig. 8 is a side and sectional view of the cylinder parts shown in Figs. 5 to 7 inclusive in an 25 assembled relationship prior to the copper brazing operation; and,

Fig. 9 is a view similar to Fig. 8 taken at right angles to the showing in Fig. 8.

For the purpose of illustrating one method of carrying our invention into effect, we have illustrated in the drawings, the construction of a cylinder for what are known as sleeve valve internal combustion engines. In Figs. 1 to 3 inclusive, the cylinder structure is shown partially 30 in an engine assemblage. In said figures, 11 represents the cylinder casing, housing and manifold of one of the cylinders of the engine. At 12, 12a, we have shown the intake ports on opposed sides of the casing and at 13, 13a corresponding exhaust ports arranged above said intake ports. Arranged in the bore 14 of the casing is a liner sleeve 15 having ports therein registering with the ports 12, 12a, 13, 13a. Slidably mounted within the liner 15 is a sleeve valve 16 35 having ports 16a, 17a adapted to register on reciprocation by means not shown with the ports 12a, 13a to open and close the intake and exhaust in the operation of engines of this type, such for example, as disclosed in United States 40 patents to Lonas No. 1,763,664, June 17, 1930, and Lonas, No. 1,686,824, Oct. 8, 1928.

At the lower end of the casing 11 is a reduced bore 18 terminating in a beveled surface 18a in connection with which a cylinder retaining ring 55

19 seats to support our improved cylinder structure 20 within the cylinder casing. The lower part 11a of the casing has at circumferentially spaced intervals, lugs 11b, in which are supported circumferentially spaced studs 11c, which pass through circumferentially spaced apertured lugs or ears 19a on the coupling ring 19 as seen in Figs. 1 and 4 of the drawings. The ring 19 has an inner corrugated surface 19b and an inwardly projecting key pin 19c for keying the cylinder structure 20 against movement with respect to said ring as well as the cylinder casing.

The cylinder structure 20 is composed of a main tubular cylinder 21, at the upper end of which is a supplemental enlarged cylinder tube 22 having a supplemental head 23. The supplemental tube 22 is centered and spaced from the cylinder 21 by outwardly extending flanges 21' on the cylinder 21 which define the periphery of ports formed in the cylinder 21 as later described. Rings 24 and 24a are also employed to space and reinforce the parts 21 and 22. Within the upper end of the tube 21 is a main head part 25 of cup shape including a bracing or reinforcing web plate 26 and spark plug housings consisting of tubular parts 27 and 28. The supplemental head 23 includes a projecting tubular extension 29 forming part of the water manifold of the cylinder.

30 The lower part of the cylinder structure has a sealing ring 30 and a corrugated sleeve 31, the latter being spun around the outwardly flared lower end 21a of the tube 21 as indicated at 31a. In this connection, it will be apparent that the 35 corrugations 31b of the sleeve 31 conform with the corrugated surface 19b of the ring 19 to form a locking or keying engagement of the cylinder structure with said ring, the sleeve 31 being apertured as indicated at 31c to receive the key pin 40 19c. The upper end of the sleeve 31 seats in a groove 30a formed in the ring 30, said ring having a large groove 30b in the outer surface thereof in which a suitable packing may be disposed.

45 The cylinder proper or tube 21 is cut out at its upper end as indicated at 21b to receive the spark plug housing part 27, and opposed side walls are cut out as seen at 21c and 21d to form intake and exhaust passages in said part, the tubular part 22 having similar openings 22a and 22b. In these openings are disposed liner rings 32, one of which is shown in Fig. 6 of the drawings in plan, and two of which are shown in section in Fig. 7 of the drawings, the latter showing being 55 disposed adjacent the openings 21c, 21d. The tubular liners 32 have curved or arc-shaped outer surfaces 32a conforming to the contour of the cylinder part 22 and curved inner surfaces 32b conforming to the contour of the wall of the 60 cylinder part 21.

In mounting these tubes in connection with the parts 21, 22 in forming the cylinder assemblage, the inner curved edges 32b are flared onto the walls of the apertures or openings 21c, 21d, in 65 the manner indicated at 32c in Fig. 9 of the drawings. Intermediate and above and below the apertures 22a, 22b, the part 22 has ring grooves 22c for receiving sealing rings or the like 33 as indicated in Fig. 1 of the drawings, it being noted 70 in this connection that the outer curved edges 32a of the port liner tubes 32 project beyond the surfaces of the part 22 to form supporting walls for the rings 33 at the port openings.

The part 22 forms in conjunction with the part 75 21 a water circulating chamber 34 which com-

municates with the water jacket 35 of the cylinder casing at the lower end of the part 22, the water circulating through apertures 24b formed in the rings 24, 24a and upwardly between the parts 21, 22 and around the head 25 as well as 5 the spark plug housings consisting of the parts 27 and 28 upwardly through the supplemental head 23 and the pipe or manifold 29. The head 25 is in the form of a cup-shaped body, the lower end of which has oppositely arranged apertures 10 25a in which the parts 28 are secured, and opposed walls have U-shaped recesses or apertures 25b which are arranged in alinement with the apertures 21b, the latter forming passages permitting the cooling water to circulate into the head 25. 15

The reinforcing and bracing web 26 consists of a plate transversing the cylinder head 25 intermediate the spark plug housings, the central portion 26a of said partition plate being reduced and the side portions apertured as seen at 26b. 20 The ends of said plate have curved edges 26c which seat in and conform with the contour of the side wall of the head 25, the lower end of the plate having foot pieces 26d seating on the domed bottom wall of the head and the lower 25 corners being recessed as seen at 26e to provide circulating passages at the bottom of the head structure.

The supplemental head 23 has downwardly flanged apertures 23a in which the upper end 30 of the tubular parts 27 are secured, the peripheral side walls or flanges 23b of said parts being secured to the inner surface or bore of the part 22 at the top thereof. It will also appear that the upper end of the part 28 is grooved as seen at 28a 35 to receive the lower end of the part 27, whereas the tubular extension of the part 28 is internally threaded as indicated at 28b to receive a spark plug or ignition device 36 such as indicated at the left of Fig. 3 of the drawings. The exploded 40 or extended view of the several parts of the cylinder structure as seen in Fig. 5 including the liner rings seen in Figs. 6 and 7 of the drawings when formed are firmly pressed together to provide the assemblage indicated in Figs. 8 and 9 of the 45 drawings.

It is understood that said parts in some instances will be pressed together under pressure to insure positive frictional engagement between the adjacent abutting walls of the separate parts, 50 and when so assembled, rings, ribbons, strips or pieces of copper or copper alloys indicated at 37 suitable for producing copper brazing are disposed in the corners or crevices or between adjacent surfaces of all of the parts as is indicated by 55 the small circles and ribbon-like deposits on Figs. 8 and 9 of the drawings. These deposits will provide a flow or capillary transmission of the brazing material employed into and between the adjacent or abutting surfaces of the separate parts 60 to copper braze said surfaces by placing the complete assemblage with the copper elements thereon in a hydrogen electric furnace heated to a suitable temperature to produce the said brazed joint between the respective parts, the temperature being at approximately 2100° Fahrenheit, but may be varied in dealing with metals or metal alloys of different kinds in the construction of the complete cylinder structure. In Fig. 1 of the drawings, I have indicated at 38 by double section lines 65 70 the copper brazed joints between the parts.

By constructing the cylinder of an engine in accordance with the method described, each part of the cylinder structure may be composed of tubing or sheet material forged or die formed into 75

the required and designated shape, thus materially reducing the manufacturing cost of the complete cylinder assemblage and at the same time providing finished surfaces upon which the piston of the cylinder operates as well as the sleeve valve, it being understood that such finished surfaces will be trued up or ground after the parts have been assembled in order to provide the desired fits and the proper alinement of the surfaces as will be apparent.

It will also appear that an engine structure of the class described by virtue of the design thereof and method of constructing the same, will produce a greater degree of thermo-symmetry by virtue of the structure and arrangement of the exhaust ports upon the cylinder from the standpoint of the circumferential area of such ports, as well as the narrowness of the ports providing a greater exposure of the walls thereof to the cooling water of the engine, producing a temperature uniformity throughout the cylinder structure. In sleeve valve engines, the arrangement of cooling manifold chambers with respect to the valve or that part of the cylinder in connection with which the valve operates also produces less distortion of the parts and eliminates leakage between the cylinder structure and sleeve valve.

By virtue of the arrangement of the head with respect to the intake and exhaust ports, relatively smooth wall lines of the combustion chamber or head end of the cylinder are formed which insure more complete and thorough exhaust of the burnt gases, and eliminate to a large degree the pocketing of spent gases within said chamber. At the same time, the intake port arrangement with respect to the head insures the most effective introduction of the combustible mixture without excessive dilution with spent gases as would otherwise be the case. The effect of this arrangement will produce by virtue of the higher combustibility of the incoming charge a greater volumetric efficiency and greater power.

The entire cylinder structure may be quickly attached and detached with respect to the cylinder casing by simply removing the ring 19, dropping the same and said cylinder structure a slight degree to displace the ring from the cylinder structure, and then pulling the entire cylinder structure upwardly through the head end thereof, it being understood that the sleeve valve and other mechanisms have been removed for this purpose. In this way, the various parts of the cylinder structure may be cleaned or repaired as well as the liner 15. By virtue of the low production cost of the cylinder structure, a new unit may be substituted for a worn one at a cost which would be possibly cheaper than the repairing of a worn unit.

It will be understood that while we have shown our invention as applied to the cylinder of an engine of a particular type or class, the invention is not necessarily limited in this respect, nor are we necessarily limited to the specific structure of the cylinder of a sleeve valve engine such as herein shown and described, and various changes therein and modifications thereof may be made within the scope of the appended claims without departing from the spirit of our invention or sacrificing its advantages.

Having fully described our invention, what we claim as new and desire to secure by Letters Patent is:

1. In an internal combustion engine, a cylinder casing, a cylinder unit detachable with respect to said casing and including a long cylin-

der tube, means at the lower end of said tube and on the wall of the cylinder casing for detachably securing the cylinder unit within and to said casing, said last named means comprising a ring seating in the cylinder casing and means thereon and on the cylinder tube for keying said tube against longitudinal and circumferential movement.

2. A cylinder unit for engines comprising a plurality of independently formed cylinder parts 10 including a cylinder proper and a head, said head being cup-shaped in form and extending into and transversing the upper end portion of the cylinder to form combustion spaces between opposite sides thereof and the walls of the cylinder, means 15 for securing said parts together, said unit including an annular sleeve encircling the head end of the cylinder and in spaced relation thereto, opposed walls of the cylinder and sleeve having one intake port and one exhaust port at 20 each side thereof opening into said combustion spaces of the cylinder, and tubular liners secured to and extending between the cylinder and sleeve for completing the ports therebetween.

3. A cylinder structure for internal combustion engines comprising a cylinder proper and a head, the head being cup-shaped in form and extending into and transversing the upper end portion of the cylinder to form combustion spaces between the walls of the inwardly extending head 30 and the cylinder wall, said combustion spaces comprising the major portion of the clearance volume and being disposed above the lower inner extending end of said head, and the minor portion of the clearance volume joining said 35 combustion spaces across the inner end of the head.

4. A cylinder structure for internal combustion engines comprising a cylinder proper and a head, the head being cup-shaped in form and extending into and transversing the upper end portion of the cylinder to form combustion spaces between the walls of the inwardly extending head and the cylinder wall, said combustion spaces comprising the major portion of the clearance 45 volume and being disposed above the lower inner extending end of said head, the minor portion of the clearance volume joining said combustion spaces across the inner end of the head, the cylinder being provided with a water circulating passage formed therearound, and means 50 for placing the lower portion of the head in communication with the water circulating passage of said cylinder to provide an upward circulation of water through said head.

5. A cylinder structure for engines comprising independently formed tubular cylinder parts arranged one within the other and spaced apart, annular members disposed between adjacent surfaces of said parts at longitudinally spaced intervals, said members serving to couple and reinforce the cylinder parts, said cylinder parts being coupled together and united to said members by copper brazed joints formed as described, and the alloy of copper forming the joints being arranged between and extending into the material of said parts and members at the abutting surfaces thereof to securely unite the same together.

6. A cylinder structure for engines comprising independently formed tubular cylinder parts arranged one within the other and spaced apart, annular members disposed between adjacent surfaces of said parts at longitudinally spaced intervals, said members serving to couple and reinforce the spaced cylinder parts, a cup-shaped 75

head extending into the inner cylinder parts, both cylinder parts having radially registering intake and exhaust ports, tubular liners mounted in both cylinder parts to complete the ports, 5 through the spaced walls of said cylinder parts, said cylinder parts, members head and liners being united by copper brazed joints formed as described to form a unit of all of said parts, an outer cylinder casing, and said unit being at- 10 tachable and detachable with respect to said casing.

7. A cylinder structure for engines, comprising an elongated cylinder part, an independent head fitting within and snugly engaging a portion of the inner surface of the wall of the cylinder part at one end thereof to provide engaging surfaces, and the engaging surfaces of the head and cylinder being united by a copper brazed joint formed as described.

20 8. A cylinder structure for engines, comprising an elongated cylinder part, an independent head snugly engaging the wall of the cylinder part at one end thereof to provide engaging surfaces, and an annular sleeve encircling the head end portion of the cylinder, annular spacing members disposed between the sleeve and cylinder and having surfaces firmly engaging said sleeve and cylinder, and all of said engaging surfaces being united by copper brazed joints formed as described.

25

30 9. A cylinder structure for engines, comprising an elongated cylinder part, an independent head snugly engaging the wall of the cylinder part at one end thereof to provide engaging surfaces, an annular sleeve encircling the head end portion of the cylinder, annular spacing members disposed between the sleeve and cylinder and having surfaces firmly engaging said sleeve and cylinder, said cylinder and sleeve having circumferentially extending intake and exhaust ports 35 arranged in common alignment, tubular liners snugly fitting in said ports and extending between the cylinder and sleeve for completing the ports therebetween, and the abutting or engaging surfaces of all of said parts being securely coupled together by copper brazed joints formed as described.

40

45

10. A cylinder structure for engines, comprising an elongated cylinder part, an independent head snugly engaging the wall of the cylinder part at one end thereof to provide engaging surfaces, an annular sleeve encircling the head end portion of the cylinder, annular spacing members disposed between the sleeve and cylinder and having surfaces firmly engaging said sleeve and cylinder, said cylinder and sleeve having circumferentially extending intake and exhaust ports arranged in common alinement, the cylinder having outwardly extending flanges bordering the edges of said ports, tubular liners snugly fitting in said ports and extending between the cylinder and sleeve for completing the ports therebetween by a supplemental head disposed above the first named head and fitting snugly in said sleeve, and the abutting surfaces of all of said parts being securely coupled together by copper brazed joints formed as described.

11. A cylinder structure for engines comprising an elongated cylinder part, an independent head snugly engaging the wall of the cylinder part at one end thereof to provide engaging surfaces, an annular sleeve encircling the head end portion of the cylinder, annular spacing members disposed between the sleeve and cylinder and having surfaces firmly engaging said sleeve and

cylinder, said cylinder and sleeve having circumferentially extending intake and exhaust ports arranged in common alinement, the cylinder having outwardly extending flanges bordering the edges of said ports, tubular liners snugly fitting in said ports and extending between the cylinder and sleeve for completing the ports therebetween by a supplemental head disposed above the first named head and fitting snugly in said sleeve, a tubular body mounted in said first named head and supplemental head and opening into said cylinder, said body forming a spark plug housing, and the abutting surfaces of all of said parts being securely coupled together by copper brazed joints formed as described. 5 10 15

12. A cylinder structure for engines comprising an elongated cylinder, a sleeve encircling said cylinder at one end portion thereof in spaced relation thereto to form an annular passage between the cylinder and sleeve, said cylinder and sleeve having on opposed walls thereof registering intake and exhaust ports disposed one above the other, tubular liners fitting snugly in the registering ports of the cylinder and sleeve and extending between the cylinder and sleeve to couple the cylinder and sleeve together and to complete the ports through the annular chamber formed between said cylinder and sleeve, and said tubular liners being secured to the cylinder and sleeve by copper brazed joints formed as described. 20 25 30

13. A cylinder structure for engines comprising an elongated cylinder, a sleeve encircling said cylinder at one end portion thereof in spaced relation thereto to form an annular passage between the cylinder and sleeve, said cylinder and sleeve having on opposed walls thereof registering intake and exhaust ports disposed one above the other, tubular liners fitting snugly in the registering ports of the cylinder and sleeve and extending between the cylinder and sleeve to couple the cylinder and sleeve together and to complete the ports through the annular chamber formed between said cylinder and sleeve, a cup-shaped head fitting snugly in the first named end portion of said cylinder and extending downwardly into and transversing the cylinder to form combustion chambers within the cylinder at opposite sides of said head and with which said intake and exhaust ports register, and said tubular liners and said head being secured in position by copper brazed joints formed as described.

14. A cylinder structure for engines comprising an elongated cylinder, a sleeve encircling said cylinder at one end portion thereof in spaced relation thereto to form an annular passage between the cylinder and sleeve, said cylinder and sleeve having on opposed walls thereof registering intake and exhaust ports disposed one above the other, tubular liners fitting snugly in the registering ports of the cylinder and sleeve and extending between the cylinder and sleeve to couple the cylinder and sleeve together and to complete the ports through the annular chamber formed between said cylinder and sleeve, a cup-shaped head fitting snugly in the first named end portion of said cylinder and extending downwardly into and transversing the cylinder to form combustion chambers within the cylinder at opposite sides of said head and with which said intake and exhaust ports register, said tubular liners and said head being secured in position by copper brazed joints formed as described to

form a cylinder unit of said parts, a cylinder casing in connection with which said unit is detachably coupled, and means involving a split ring engaging the lower end portion of the cylinder and said cylinder casing for securing the cylinder unit within said casing.

5 15. A cylinder unit comprising an elongated cylinder tube, a head permanently fixed to one

end of said tube and including a cup-shaped sheet metal body extending downwardly into the tube and spaced from opposed walls of said tube to form independent circumferentially extending passages between said body and opposed walls of the cylinder tube.
